US0D1092808S

(12) **United States Design Patent** (10) **Patent No.:** **US D1,092,808 S**
(45) **Date of Patent:** **** Sep. 9, 2025**

(54) **LIGHT**

(71) Applicant: **Dometic Sweden AB**, Solna (SE)
(72) Inventors: **Christian Zachrich**, Bromma (SE);
Luis Kobayashi, Kungsängen (SE);
Steve Schwennsen, Seattle, WA (US)
(73) Assignee: **Dometic Sweden AB**, Solna (SE)
(**) Term: **15 Years**
(21) Appl. No.: **29/838,379**
(22) Filed: **May 12, 2022**

(30) **Foreign Application Priority Data**

(57) **CLAIM**

The ornamental design for a light as shown and described.

DESCRIPTION

FIG. 1 is a first perspective view of a light in an open state; FIG. 2 is a second perspective view of the design in a closed state;

FIG. 3 is a front view of the design of FIG. 2;

FIG. 4 is a rear view of the design of FIG. 2;

FIG. 5 is a first side view of the design of FIG. 2;

FIG. 6 is a second side view of the design of FIG. 2; and, FIG. 7 is a top view of the design of FIG. 2.

The broken lines immediately adjacent to the claimed areas depict the bounds of the claimed design, while all other broken lines are directed to environment. The broken lines form no part of the claimed design.

1 Claim, 7 Drawing Sheets
